(57) **CLAIM**

The ornamental design for a protective lens assembly as shown and described.

DESCRIPTION

FIG. 1 is a rear right perspective view of the mount portion of my new design for a protective lens assembly;

FIG. 2 is a front right perspective view of the mount portion of FIG. 1;

FIG. 3 is a right side elevational view of the mount portion of FIGS. 1 and 2;

FIG. 4 is a left side elevational view of the mount portion of FIGS. 1 and 2;

FIG. 5 is a front elevational view of the mount portion of FIGS. 1 and 2;

FIG. 6 is a rear elevational view of the mount portion of FIGS. 1 and 2;

FIG. 7 is a rear right perspective view of the lens portion of my new design for a protective lens assembly;

FIG. 8 is a front right perspective view of the lens portion of FIG. 7;

FIG. 9 is a right side elevational view of the lens portion of FIGS. 7 and 8;

FIG. 10 is a left side elevational view of the lens portion of FIGS. 7 and 8;

FIG. 11 is a front elevational view of the lens portion of FIGS. 7 and 8;

FIG. 12 is a rear elevational view of the lens portion of FIGS. 7 and 8;

FIG. 13 is a rear right perspective view of the combination of the mount portion of FIGS. 1-6 assembled together with the lens portion of FIGS. 7-12 to form the protective lens assembly;

FIG. 14 is a front right perspective view of the protective lens assembly of FIG. 13;

FIG. 15 is a right side elevational view of the protective lens assembly of FIGS. 13 and 14;

FIG. 16 is a left side elevational view of the protective lens assembly of FIGS. 13 and 14;

FIG. 17 is a front elevational view of the protective lens assembly of FIGS. 13 and 14; and,

FIG. 18 is a rear elevational view of the protective lens assembly of FIGS. 13 and 14.

(Continued)

The evenly dashed broken lines shown in the drawings illustrate portions of the article and form no part of the claimed design. The dot-dash broken lines shown in the drawings illustrate boundaries of the claimed design and form no part thereof.
